AUTOMATIC SUBSTATION TELEPHONE CIRCUIT

Filed June 7, 1922

— Inventor —

Arthur Bessey Smith

Chas. W. Candy Atty.

UNITED STATES PATENT OFFICE.

ARTHUR BESSEY SMITH, OF EVANSTON, ILLINOIS, ASSIGNOR TO AUTOMATIC ELECTRIC COMPANY, OF CHICAGO, ILLINOIS, A CORPORATION OF ILLINOIS.

AUTOMATIC SUBSTATION TELEPHONE CIRCUIT.

Application filed June 7, 1922. Serial No. 566,563.

To all whom it may concern:

Be it known that I, ARTHUR BESSEY SMITH, a citizen of the United States of America, and a resident of Evanston, Cook

5 County, and State of Illinois, have invented certain new and useful Improvements in Automatic Substation Telephone Circuits, of which the following is a specification.

10 The present invention relates to automatic substation telephone circuits, and the object, briefly stated, is the provision of new and improved circuits for an automatic telephone substation, whereby an existing manual telephone having the usual three spring switch-hook combination can be changed into an automatic telephone by the addition of a calling device having the usual three spring shunt spring combination.

15 20 Circuits have been devised before which utilize the standard three spring switch-hook combination on an existing manual telephone set of the usual booster type when the telephone is changed to an automatic telephone by the addition of a suitable called device. So far as applicant knows, however, all the prior substation circuits of the above mentioned type require a special calling device having two pairs of shunt 25 springs insulated from each other. The present case differs from the preceding ones in that only three shunt springs are used on the calling device, which calling device, accordingly, may be of standard make.

30 35 The improved circuits will now be described with reference to the accompanying drawings comprising Figs. 1 and 2, in which Fig. 1 is a simplified diagram of the improved substation circuit, and Fig. 2 is a winding diagram of a manual desk telephone converted into an automatic telephone by the addition of a standard calling device and by suitable changes in the wiring to conform with the circuit shown in Fig. 1.

40 45 Referring now particularly to Fig. 1, the bell B and condenser C are permanently bridged across the line conductors 2 and 3 according to well known practice. When the receiver is removed, a direct current bridge is closed across the line conductors 2 and 3 at the switch-hook 10 and spring 11, and includes the upper winding of the induction coil I, the transmitter T, and springs 4 and 5 of the calling device CD.

Also, switch-hook 10 and contact 9 shunt 35 the receiver R and the lower winding of the induction coil I, in series with the condenser C, around the transmitter T.

45 50 In case the subscriber is making a call, he operates his calling device CD in the usual manner, and when the dial is turned from its normal position, shunt springs 6, 7, and 8 make contact with each other in the usual manner. Springs 6 and 7, upon coming together, shunt the receiver R so 55 as to eliminate undesirable clicking. Springs 7 and 8, upon coming together, shunt the transmitter T so as to lower the resistance of the bridge across conductors 2 and 3. As the dial of the calling device 60 rotates back to its normal position, the bridge across conductors 2 and 3 is opened the desired number of times at springs 4 and 5, and when the normal position is reached, springs 6, 7 and 8 separate, thereby 65 removing the shunt from around the receiver R and the shunt from around the transmitter T.

70 75 It may occur occasionally that a subscriber, knowing that the receiver must be removed before a call can be made, operates his calling device with the receiver on the hook, thinking of course that no harm is being done. When the present substation circuit is used, however, the automatic 80 switches are operated when the calling device is turned, regardless of whether the receiver is off the switch-hook or not. This is due to the fact that shunt springs 6 and 7, upon coming into engagement with each 85 other when the calling device is turned, shunt switch-hook 10 and spring 9, thereby closing a circuit across line conductors 2 and 3, through the bell B and the lower winding of the induction coil I. Then, as 90 the calling device returns to normal position, the bridge across the line conductors is interrupted in the usual manner. However, the subscriber is warned that he is 95 doing something he should not do by the tapping of the bell B which is operated at this time because it is not shunted by the upper winding of the induction coil I. The subscriber, upon hearing the tapping 100 of the bell B, knows that he is doing something wrong and refrains from idly operating the calling device CD. Of course, the bridge across the line conductors 2 and 3 is 105

opened again when the calling device CD returns to normal position, and the exchange switches are again released.

Referring now to Fig. 2, which is a wiring diagram of the substation shown in Fig. 1, the equipment shown on the left comprising the bell B, the condenser C, the induction coil I, and the associated terminal strip, is located in the bell box of an ordinary desk telephone and is connected to the desk stand by a three conductor cord. The equipment in the desk stand comprises the transmitter T, receiver R, calling device CD, switch-hook springs 9, 10, and 11, and the associated terminal strip. The wiring diagram may be readily checked up with the schematic diagram because of the fact that like reference characters indicate like parts.

What is claimed is:

1. In a substation telephone circuit, two line conductors, a bell and a condenser bridged permanently across said conductors, an induction coil having two windings, one of said windings being in series with one of said line conductors, a calling device having control contacts, a transmitter, said control contacts and said transmitter being connected in series in the other of said line conductors, a receiver, a third conductor connected at one end to a point between said bell and said condenser, the other winding of said induction coil and said receiver connected in series in the order named in said third conductor, three switch hook contacts at each of which a different one of said conductors terminates, said contacts adapted to close together when said receiver is lifted, and three shunt contacts on said calling device adapt-

ed to close together when said device is off normal, one of said shunt contacts connected to one side of said transmitter, the second shunt contact permanently connected to the other side of said transmitter, and the third shunt contact connected between said receiver and said other winding. 40 45

2. In a substation telephone circuit, two line conductors, a bell and a condenser bridged across said conductors, an induction coil having two windings, one of said windings being in series with one of said line conductors, a calling device having control contacts, a transmitter, said control contacts being connected in series in the other of said line conductors at a point between the condenser and the said transmitter, a receiver, 50 a third conductor connected at one end to a point between said bell and said condenser, the other winding of said induction coil and said receiver connected in series in said third conductor, three switch-hook contacts at 60 each of which a different one of said conductors terminates, said contacts adapted to make contact with each other when said receiver is lifted, three shunt contacts on said calling device adapted to make contact with 65 each other when said device is off normal, one of said shunt contacts permanently connected to one side of said transmitter, the second shunt contact permanently connected to the other side of said transmitter, and the third shunt contact connected between said receiver and said other winding. 70

In witness whereof, I hereunto subscribe my name this 31st day of May, A. D., 1922.

ARTHUR BESSEY SMITH.
